UNITED STATES PATENT OFFICE

JACOB BECKER, OF PORTLAND, OREGON

DOOR OPENER

Application filed December 16, 1930. Serial No. 502,727.

My invention relates to door openers in which a ratchet mechanism and a toggle joint are connected with a door, and in which mechanically operated cables from a distantly located starting post lead to the ratchet mechanism.

The objects of my invention are to produce a device by means of which one, or several doors simultaneously, can be opened or closed from a distance; which is operated mechanically, that is, without the intervention of any motor, so that this device can be used where automatic power of any description is not available or desirable; which can be locked to prevent unauthorized use; which can be operated by an automobile driver from his seat; and with which even heavy doors can be handled by a woman or a child.

Other objects and advantages are to be found in the construction and arrangement of parts as will be described in the specification and particularly pointed out in the appended claims.

I attain these objects with the mechanism, illustrated in the accompanying drawings, in which:

Fig. 1 shows, in elevation, the relative positions of a garage and the starting post.

Fig. 2 is a broken plan view of Fig. 1 with the essential details shown on an enlarged scale.

Fig. 3 is a partial elevation of Fig. 2 along the line 3—3.

Fig. 4 is an elevation of the shaft driving mechanism.

Fig. 5 is a perspective view of Fig. 4 with some of the elements separated from each other in order to show various pertinent details more clearly.

Fig. 6 is a vertical section through the head of the starting post with the crank in half-way position.

Fig. 7 is a perspective view of one of the pulleys in Fig. 6, but returned to normal or starting position.

Fig. 8 is a section through Fig. 6 along the line 8—8.

Similar numerals refer to similar parts throughout the several views.

50 Referring to Fig. 2, a shaft 1 in suitable

bearings 2 is attached to the lintel 3 of the door frame, parallel to the closed doors 4. For each door there is provided, on the shaft 1, a worm 5, which engages a worm wheel 6, and thereby operates a toggle joint 7 whose one end is firmly affixed to the bottom of the worm wheel 6, while the other end is pivotally attached to the side of the door 4. At one end of the shaft 1 is a driving mechanism the details of which are illustrated in Figs. 4 and 5, and which consists of a small gear 8 firmly mounted on the shaft 1 and a large gear 9 rotatably mounted on the gudgeon 10. Each side of this large gear 9 has radially directed ratchet teeth 11 and 12, with the teeth on one side pointing in one direction while the teeth on the other side point in opposite direction. Also rotatably mounted on the gudgeon 10, are two pulleys 13 and 14, one on each side of the large gear, 9. To the periphery of the pulley 13 is attached a radially slideable pawl 15 and to the pulley 14, a radially slideable pawl 16, said pawl being adapted to engage the ratchet teeth 11 and 12 respectively. Normally the pawl 15 is held in elevated position by a compression spring such as shown at 17 and which is inserted between the hub of the pulley 13 and the pawl 15. Pawl 16 has a similar arrangement. A cable 18 is led over the upper half of the pulley 13 and over the top of the pawl 15. A similar arrangement prevails between cable 19, pulley 15, and pawl 16. Cables and pawls are firmly connected with each other in any suitable manner. One end of each cable 18 and 19 is attached to a tension spring such as shown at 20 in Fig. 1 and which may be anchored in any suitable manner to the ground or to the garage wall 21 as shown in Fig. 1. The other end of each cable 18 and 19 leads through an underground conduit 22 equipped with suitable anti-friction devices to a starting post, in the head 23 of which are two pulleys 24 and 25. The ends of the two cables 18 and 19 from the driving mechanism are attached to blocks 26 and 27 (Figs. 6 and 7) on the rims of these two pulleys 24 and 25 so that upon partial rotation of one pulley, the cable pertaining thereto will be wound partly around the rim. The hub of each

pulley 24 and 25 is slotted as shown at 28 in Fig. 7, so as to permit of the reception of a locking device. The barrel 29 on which the two pulleys 24 and 25 are freely mounted is 5 itself revolvably mounted in the side walls of the head 23 and rotated by means of a crank 30. In the barrel are the T-bolts 31 and 32 for the pulleys 24 and 25 respectively. Normally the T-bolts 31 and 32 are held in re- 10 tracted position by the compression springs 33 and 34 around the T-bolts. However, if a flat key 35 with a suitable bit 36 is inserted in the barrel 29 and turned ninety degrees the T-bolt 31 is raised into the slotted hub 28 and 15 the pulley 24 is compelled to follow the movement of the crank 30. A similar bit 37 for the other pulley 25 is provided on the opposite edge of the key 35. The rotatable, slotted pin 38 which guides the proper key into 20 the barrel 29 is held in place by a screw 39 at the rear end of the pin 38.

To close the door, the key 35 is inserted into the barrel 29 so that the bit 36 will lift the T-bolt 31 into the door-closing pulley 24. 25 Thereupon the crank 30 is moved a hundred and eighty degrees until arrested by the stop 40 (Fig. 2) on the outside of the head 23. The movement of the crank 30 will exert a pull on the cable 18 which will first depress 30 the pawl 15 in the pulley 13 to engage one of the ratchet teeth 11; as the pull in the cable 18 continues, the large gear 9 will begin to rotate and to transmit its rotation to:—the small gear 8, the shaft 1 with its worm 5, and 35 the worm gear 6, and thereby actuate the toggle joint 7 which tends to close the door 4. The return of the crank 30 to normal starting position is accomplished by the tension spring 20 at the other end of the cable 18; the movement of the crank 30 is repeated until the door 4 is fully closed.

To open the door the key is taken out and reinserted so that the other bit will actuate the T-bolt for the door-opening pulley, then 45 the crank is moved as before and the pawl will be brought in contact with the ratchet teeth pointing in opposite directions, so that the movements of the large gear and of all the other elements dependent upon the movement 50 of the large gear are reversed, and the door opened. The actual working pull in this case however will be exerted by the tension spring at the opposite end of the cable; the crank is merely used to pull the pawl to the 55 proper tooth of the ratchet wheel, after which the tension spring does the actual work of turning the large gear.

The shaft driving mechanism is enclosed by a hood 41 as shown in Fig. 1 to furnish 60 the bearings for the gudgeon 10.

The washer 42 (Fig. 2) holds the barrel 29 and the slotted pin 38 in the head 23.

Having thus described my invention, it 65 will be seen that my objects have been accomplished and though I have shown the pre-

ferred form of construction, I reserve to myself the right to make minor changes, providing I do not contravene the spirit and principle of my invention.

I claim:

1. In a door opener, the combination of a starting post including a head, a pulley rotatably mounted in the head, a barrel rotatably mounted in the head and freely supporting the pulley, a crank rigidly attached to the barrel at the outside of the head, a slotted pin rotatably mounted at the axis of the barrel, a flat key inserted in the slotted pin, said key having a bit, a radially extended T-bolt slidably mounted in the barrel, a compression spring around the T-bolt holding said T-bolt normally in retracted position, said key upon a turn of ninety degrees being adapted to project the T-bolt; said pulley having a slotted hub adapted to be engaged by the projected T-bolt. 70

2. In a door opener, the combination of a starting post including a head, a barrel rotatably mounted within the head, a crank rigidly attached to the barrel at the outside of the head, a radially extending T-bolt slidably mounted in the barrel, a pulley freely mounted on the barrel, said pulley having a slotted hub, and means to raise the T-bolt into the slotted hub to connect the pulley with the barrel so that the pulley rotates in unison with the movement of the crank. 75

3. In a door opener, the combination of opening and closing means attached to the door, said means including a cable, a distantly located starting post at one end of the cable, said starting post including a head, a pulley mounted in the head, said cable being attached to the pulley, a barrel rotatably mounted in the head, a crank attached to the barrel and locking means between the barrel and the pulley. 80

4. In a door opener, the combination of a shaft, a door, foldable connecting means between shaft and door, a driving mechanism at the end of the shaft, a cable to actuate the driving mechanism, a distantly located starting post, a pulley in the starting post, said cable being firmly affixed to the pulley, a crank cooperating with the pulley to exert a pull on the cable, and locking means to engage and disengage the crank from the pulley, said locking means including a safety key. 85

5. In a door opener, the combination of a shaft, a door, folding connections between shaft and door, a driving mechanism at the end of the shaft, said driving mechanism including a pawl and ratchet device, a cable firmly affixed to the pawl, and actuating the ratchet, a tension spring attached to one end of the cable, a distantly located crank attached to the other end of the cable, and operating means between the crank and the cable. 90

6. In a door opener, the combination of a rotating shaft, a door, a toggle point between the shaft and door, a driving mechanism at the end of the shaft, said driving mechanism comprising a small gear on the shaft, a larger gear engaging the small gear, radially extending ratchet teeth in each side of the large gear, the teeth on one side pointing in a direction opposite to those of the other side, a pulley on each side of the large gear, a radially directed pawl slidably mounted in the rim of each pulley, said pawl being adapted to engage the ratchet teeth, a compression spring in the pulley, holding the pawl normally free of the ratchet teeth, a cable leading over the pulley and over the top of the pawl, and distantly located means to exert a manual pull on the cable and bring the pawl in contact with the ratchet teeth.
- 10 7. In a door opener, the combination of a door frame, a door in the door frame, a horizontal shaft attached to the door frame and parallel to the closed door, a worm firmly affixed to the shaft, a worm gear rotated by the worm, a toggle-joint between the worm gear, and the door, driving mechanism at the end of the shaft, and distantly located means to operate the driving mechanism manually.
- 20 8. In a door opener, the combination of a door frame, a horizontally swinging door in the door frame, a horizontal shaft attached to the door frame, and parallel to the closed door, a toggle-joint pivotally affixed to the door and operated by the shaft, a driving mechanism at the end of the shaft, a distantly located starting post, an underground conduit between the starting post and the driving mechanism, a cable from the starting post proceeding through the underground conduit to the driving mechanism, a crank in the starting post, and operating means between the cable and the crank, said operating means including, a pulley having a slotted hub, and a barrel having a reciprocating T-bolt, to engage the slotted hub.
